UNITED STATES PATENT OFFICE.

JOHN P. DORAU, OF JEFFERSON, WISCONSIN.

DRIVING MECHANISM FOR WASHING-MACHINES.

1,273,336.

Specification of Letters Patent. Patented July 23, 1918.

Application filed July 2, 1917. Serial No. 178,224.

To all whom it may concern:

Be it known that I, JOHN P. DORAU, a citizen of the United States, and resident of Jefferson, in the county of Jefferson and 5 State of Wisconsin, have invented new and useful Improvements in Driving Mechanism for Washing-Machines, of which the following is a description, reference being had to the accompanying drawings, which 10 are a part of this specification.

The invention relates to driving mechanism, and more particularly to a driving mechanism for a washing machine.

It is one of the objects of this invention 15 to provide a driving mechanism for operating the shaft carrying the clothes pounder so as to revolve the pounder shaft in one direction during several agitations and vertical reciprocations of said pounder and 20 then revolve said shaft in the opposite direction during several agitations and vertical reciprocations of the pounder with the result that the pounder will strike the clothes in different places and thus more 25 efficiently accomplish the washing operation than in that type of washing machine in which the pounder always strikes the clothes in the same place.

A further object of the invention is to 30 provide a yielding connection between certain of the parts constituting the driving mechanism to permit the pounder to yield under excessive pressure.

The invention further consists in the several features hereinafter set forth.

In the drawings:

Figure 1 is a view of the device embodying the invention, parts being broken away and parts being shown in section;

40 Fig. 2 is a section taken on the line 2—2 of Fig. 1;

Fig. 3 is a section taken on the line 3—3 of Fig. 1;

Fig. 4 is a section taken on the line 4—4 of Fig. 1;

Fig. 5 is a view, partly in section, of a modified form of driving mechanism;

Fig. 6 is a section taken on the line 6—6 of Fig. 5;

50 Fig. 7 is a view, partly in section of another modified form of device;

Fig. 8 is a section taken on the line 8—8 of Fig. 7;

55 Fig. 9 is a section taken on the line 9—9 of Fig. 8.

The washing machine to which the driv-

ing mechanism is applied consists of a tub 10 and hinged cover 11 all of usual construction, said cover carrying a bracket 12 in which the pounder shaft 13 is vertically, 60 slidably and rotatably mounted, said shaft carrying a pounder 14 of any suitable construction. A horizontal drive shaft 15 is journaled in the bracket 12 and carries a gear 16 in mesh with a gear 17 integral with 65 a fly wheel 18 journaled on a stud shaft 19, said fly wheel being provided with a groove 20 in which a round rubber band 21 is inserted and which band is adapted to be frictionally engaged by the wheel of a motor (not shown). The construction above described serves to continuously rotate the drive shaft 15. However any other suitable means may be used to impart movement to said shaft 15. 70

The invention resides in the driving connection between the drive shaft 15 and the pounder shaft 13.

In each form of the invention this driving connection includes a member having 80 an automatically reversible driving connection with the pounder shaft and an offset joint connection with the drive shaft 15.

In Figs. 1 to 4 inclusive I have illustrated the preferred embodiment of this driving 85 connection. In this instance the member consists of a shaft 22 journaled in a bearing 23 and carrying a gear 24 at one end and a spherical knob 25 at its other end. The bearing 23 is pivotally secured at one end 90 to a housing 26 by a pipe 27, said housing having arms 27 through which the shaft 13 passes and said bearing is also provided with an eccentric 28 mounted thereon to permit a slight rocking movement and provided with a finger 29. The joint connection 95 between the member and the shaft 15 consists of a crank 30 carried by said shaft and provided with a bore 31 in which the knob 25 is slidably and pivotally mounted, said 100 knob carrying a pin 32 slidably mounted in aligned slots 33 in said crank. This offset joint connection produces a back and forth or agitating movement of the pounder together with an up and down movement. In 105 order to relieve the pounder of excessive load I have provided a yielding connection between the driving connection and the shaft 15 which is formed by slidably mounting the crank 30 in a bore 34 in a member 110 35 mounted by said shaft and interposing a spring 36 between said member 35 and

the crank 30 to permit relative yielding movement, the crank being guided and retained in operative position by a guide rod 37 and a guide and spring retaining rod 38.

- 5 The gear 24 is adapted to be brought into mesh with either of two oppositely disposed bevel gears 39 and 40 spaced apart and fixed to the shaft 13, one of said gears carrying a pin or finger 41 adapted to engage the finger 29 on the eccentric 28 to turn said eccentric and consequently the bearing 23 to bring the gear 24 into contact with either the gear 39 or 40.

With this construction as the shaft 15 is 15 rotated it will through the joint connection with the shaft 22 rotate the gear which being in mesh with the gear 39 will rotate said gear to make one complete revolution of the pounder shaft during several agitations and 20 vertical reciprocations of said shaft 13 after which the finger 41 will strike the finger 29 oscillating the eccentric 28 which in turn moves the bearing 23 upwardly disengaging the gear 24 from the gear 39 and bringing 25 said gear 24 into mesh with the gear 40 which then imparts a reverse rotation to the pounder shaft for one revolution during several agitations and vertical reciprocations of the shaft 13 at the end of which time the finger 41 strikes the other side of the finger 29 thereby shifting the eccentric 28, bearing 23 and shaft 22 to bring the gear 24 into mesh with the gear 39 again and repeat the operations.

- 30 The constructions shown in Figs. 5 and 6 is similar to that previously described except that the reversible gear drive consists of a ratchet wheel 42 fixed to the shaft 13 and provided with a projection or finger 43, 40 a double pawl 44 pivotally mounted on a vertical pin 45 carried by a member 26' having arms 27' through which the shaft 13 passes, said member having a shaft 22' integral therewith and provided with a 45 knobbed end 25 which is slidably and rotatably mounted in the bore 31 of the crank 30. This offset joint connection produces an agitation of the pounder together with an up and down movement. The pawl 44 is 50 provided with a shifting arm or finger 46 which is acted upon by a spring 47 connected to the member 26' and to a rod 48 connected to said finger, said spring serving to pull the finger 46 and double pawl 44 over dead center and to keep one pawl in engagement with the ratchet wheel 42.

With this construction as the shaft 15 is 55 rotated it will through the joint connection with the member 26' shift one of the pawls 60 to move the ratchet wheel 42 one tooth at a time during the agitation and vertical reciprocation of the pounder shaft until finally said shaft with the ratchet has made one complete revolution at which time the finger 43 strikes the arm 46 reversing the posi-

tion of the pawls and thereby causing a revolution of the pounder shaft in the reverse direction during several agitations and vertical reciprocations of the pounder shaft.

The construction shown in Figs. 7 to 9 inclusive is similar to that of Figs. 1 to 4 inclusive except that the shaft 22 is connected to the pounder shaft for reversely operating it by reverse mangle gearing consisting of the pin gear 24' carried by said shaft 22 and 70 a mangle rack 49 having upper and lower annular guide grooves 50 for receiving the end 57 of the shaft 22, a plurality of pins 52 between the grooves and grooves 53 connecting the grooves 50 whereby the gear 24' 75 while running in the upper groove will engage the pins 52 to rotate the pounder shaft 13 in one direction and then the end 51 passes down through one of the grooves 53 into the lower groove and engages the pins to 80 rotate the pounder shaft in the opposite direction, and then returns to the upper groove to repeat the operation. It will thus be seen that this construction gives an automatic reversal to the pounder shaft after 85 every revolution while said shaft is being agitated and vertically reciprocated. It will also be noted that in this construction the mangle gearing takes the place of the gears 24, 39 and 40, the eccentric 28 and the fingers 29 and 41.

Thus in each of the forms above described during the continuous rotation of the drive shaft 15 there is a turning of the pounder shaft in one direction for about one revolution during several agitations of the pounder and vertical reciprocations of the pounder shaft through the ball and crank joint connection, and then in the reverse direction for about one revolution during several agitations of the pounder and vertical reciprocations of the pounder shaft. Of course it will be apparent that instead of one stop which permits of almost one revolution of the pounder shaft, two stops might be used 100 so as to cause only a partial revolution in one direction and then a reverse partial revolution in the other direction. Since the pounder moves back and forth and up and down as it rotates it strikes the clothes in 105 different places during its movements and thereby efficiently cleans them.

The invention thus exemplifies a new and improved form of driving mechanism particularly adapted for use in connection 110 with washing machines.

What I claim as my invention is:

1. In a driving mechanism, the combination, with a vertical shaft, of a drive shaft disposed at an angle thereto, and a driving connection between said shafts for imparting a rotary movement in one direction to said vertical shaft during several oscillations and vertical reciprocations of said vertical shaft and for imparting rotary move- 125 130

ment in the opposite direction to said vertical shaft during several oscillations and vertical reciprocations of said vertical shaft.

2. In a driving mechanism, the combination, with a vertical shaft, of a drive shaft disposed at an angle thereto, and a driving connection between said shafts comprising a member having an offset joint connection with one of said shafts and an automatically reversible driving connection with the other of said shafts.

3. In a driving mechanism, the combination, with a vertical shaft, of a drive shaft disposed at an angle thereto, and a driving connection between said shafts comprising a member having a yieldingly mounted offset joint connection with one of said shafts and an automatically reversible driving connection with the other of said shafts.

4. In a driving mechanism, the combina-

tion, with a vertical shaft, of a drive shaft disposed at an angle thereto, and a driving connection between said shafts comprising a member having an automatically reversible gear drive connection with the vertical shaft 25 and an offset connection with the drive shaft.

5. In a driving mechanism, the combination, with a vertical shaft, of a drive shaft disposed at an angle thereto, and a driving connection between said shafts comprising a 30 member having an offset connection with the drive shaft and carrying a gear, a pair of reverse gears carried by the vertical shaft, and means for automatically bringing said first named gear into alternate driving engagement with the gears on the vertical shaft.

In testimony whereof, I affix my signature.

JOHN P. DORAU.
